UNITED STATES PATENT OFFICE.

WILLIAM HADWEN AMES, OF NORTH EASTON, MASSACHUSETTS.

HYDROCARBON-BURNER.

SPECIFICATION forming part of Letters Patent No. 516,070, dated March 6, 1894.

Application filed May 21, 1892. Renewed November 29, 1893. Serial No. 492,394. (No model.)

To all whom it may concern:

Be it known that I, WILLIAM HADWEN AMES, residing at North Easton, in the county of Bristol and State of Massachusetts, have 5 invented certain new and useful Improvements in Hydrocarbon-Burners; and I do hereby declare the following to be a full, clear, and exact description of the invention, such as will enable others skilled in the art to which 10 it appertains to make and use the same.

Figure 1 is a sectional view of the burner; and Figs. 2, 3, and 4 are views showing two propellers.

This device belongs to the class called hydro-carbon burners, which are chiefly used in furnaces, and the novelty consists in the structure of their several parts, in their combination with each other, and the device as a whole; all as will be described and pointed 20 out in the claims. As this device, like my former one, is attached to the furnace in any well-known or usual way, it is not necessary now to show anything but the burner itself, and generally designate how it may be applied to the furnace.

In the drawings, A, denotes a flange by which the burner is bolted to the furnace. The nozzle B is suitably attached to this plate, at about its center, and at the rear of it is a 30 gauze plate chamber B' which, with necessary changes in mere size and shape, is but a continuation of the nozzle B. On the floor of this chamber B' is a rack b, and in the upper part of the chamber are openings b'. Over 35 the latter is a cover E, which can be secured in place by screw-bolts or otherwise. Through the openings b' are placed screens or atomizers C, C', C². In this device I arrange screens or atomizers as in my Patent No. 465,746, but 40 introduce the oil pipe D through the elbow L into the chamber B', and at the end of the pipe, which is at a suitable distance from the screens C, C', C², one or more orifices, o, o, are made, through which the oil comes to the 45 surface of the pipe. In the end of the pipe, next to the screens is a pin on which is placed one or more propellers or spreaders P, P'. The air blast takes up the oil from the pipe at o, o, and blowing it against the propellers 50 P, P', which are rapidly revolved by action of the air or steam blast, is spread in a spray over the surface of the screens, C, C', C², and

in its subsequent passage through the meshes of the screens is more fully and perfectly atomized, and the air becomes uniformly charged with the minute particles of oil, and a more intense and steady fire is obtained with a less consumption of oil than when the air is not so perfectly and uniformly saturated.

In this device, the novelty consists in the introduction of the oil into that part of the chamber B' immediately in front of the screens or atomizers C, C', C² in a horizontal position, the oil pipe being perforated with small holes o, o, and terminating with one or more propellers P, P'.

When using two propellers, I find, in practice, the best results are obtained by having them revolve in contrary directions. This 70 modification, (improvement of my former patent,) is easily arranged at small cost, and is easily cared for.

Having now described my invention, I 75 claim—

1. A hydro-carbon burner for furnaces or steam boilers, having interposed between the oil-supply pipe and the nozzle several wire gauze or finely perforated plates, of suitable mesh or perforation, and one or two propellers, with means for connecting them with the oil pipe and air blast apparatus, substantially as set forth.

2. In combination, a burner provided with an oil-feed pipe, projecting horizontally into 85 a chamber, and terminating with oil holes, and one or more propellers; wire gauze or perforated plates, and supplemental air blast, separated from the chamber holding the propellers and atomizers, and ending close to 90 the lower edge of the nozzle, substantially as set forth.

3. In combination with chamber B', having a rack b on its bottom, and in its upper part openings b', the oil-pipe D, the propellers P, P', and the gauze or perforated plate C, C', C², placed in position in the manner and for the purposes set forth.

In testimony whereof I affix my signature in presence of two witnesses.

WILLIAM HADWEN AMES.
